Arthur V. Briesen

UNITED STATES PATENT OFFICE.

ARTHUR v. BRIESEN, OF NEW YORK, N. Y.

BRACELET.

SPECIFICATION forming part of Letters Patent No. 334,844, dated January 26, 1886.

Application filed January 15, 1885. Serial No. 152,952. (No model.)

To all whom it may concern:

Be it known that I, ARTHUR VON BRIESEN, a resident of New York city, in the county and State of New York, have invented an Improved Bracelet, of which the following is a full, clear, and exact description, reference being made to the accompanying drawings, in which—

Figures 1 and 2 are perspective views of my improved bracelet, and Fig. 3 is a sectional view of part of the same.

This invention has for its object to relieve ladies from the burden of carrying pocket-books in their hands, or of searching for them in their pockets when called upon to pay fares and the like. Considerable inconvenience is experienced by ladies, especially when they have to carry bundles, parasols, or the like, in their endeavors to reach their purses for paying their way as they go along.

My invention consists in a bracelet that carries a receptacle of the special kind herein-after described.

The bracelet A which is shown in the drawings may be constructed of leather, nicely ornamented, or any other suitable flexible material. It should be so arranged that it can be worn around the wrist over the glove. On the front or inner side of the wrist this bracelet A is provided with a small receptacle, B, which is rigidly attached thereto, said receptacle

having a lid, C, which has a catch, a, that is closed by a spring-button, b. The receptacle B is adapted to contain a small number of coins. The bottom of this receptacle is formed by the 35 body of the bracelet, as shown. The wearer of this bracelet in order to get at the contents of the receptacle will only have to turn the hand palm upward, and then touch the spring-button b, when the lid C will fly open under 40 the influence of a small spring, d, thereby disclosing the contents of the receptacle. It will be seen that the receptacle B does not in any manner serve to hold the hinged ends of the bracelet, as is the case with the bracelet shown 45 in Patent No. 267,851, which I disclaim. For this purpose, a separate buckle, D, or equivalent fastening is used in my flexible bracelet apart from the receptacle.

I claim—

The flexible bracelet A, constructed to form a coin-receptacle, B, rigidly connected thereto, the body of the bracelet extending beneath said receptacle to form a bottom or support for the same, said bracelet having a fastening, D, apart from said receptacle, as set forth.

ARTHUR v. BRIESEN.
